C. A. RASMUSSEN & R. M. CLARK.

TOOL FISHING SOCKET.

APPLICATION FILED OCT. 28, 1914.

1,170,329.

Patented Feb. 1, 1916.

UNITED STATES PATENT OFFICE.

CHESTER A. RASMUSSEN AND ROBERT M. CLARK, OF YENANGYAUNG, UPPER BURMAH,
INDIA.

TOOL-FISHING SOCKET.

1,170,329.

Specification of Letters Patent.

Patented Feb. 1, 1916.

Application filed October 28, 1914. Serial No. 869,124.

To all whom it may concern:

Be it known that we, CHESTER A. RASMUSSEN and ROBERT M. CLARK, machinists of the Burmah Oil Company, Ltd., and residents of Yenangyaung, Upper Burmah, India, have invented certain new and useful Improvements in Tool-Fishing Sockets, of which the following is a specification.

This invention relates to the drilling of wells, and the object thereof is to provide a socket for attachment to a tool, which has become detached from the operating cable, and subsequent removal from a well.

A further object is to construct the socket so as to be readily detached from a tool so firmly lodged as to resist all efforts at removal, and refusing to yield to pulling and jarring, to allow the withdrawal of the socket only from the well; and a further object is to provide a frangible element, within the socket, which does not interfere with the normal operation of the socket but which, when broken, renders the tool attaching devices of the socket inoperative to allow 25 of the withdrawal of the socket from the well.

The invention is fully described in the following specification, of which the accompanying drawings form a part, in which the 30 separate parts are designated by the same reference characters in each of the views, and in which:—

Figure 1 is a side elevation of the invention, partly-broken away to show structural details; Fig. 2 is an enlarged section taken on the line 2—2 of Fig. 1; Fig. 3 is a section taken on the line 3—3 of Fig. 2; Fig. 4 is an end view, at the tool engaging end; and Fig. 5 is an enlarged view of a slight modification of a detail, and adapted for large sizes of tools.

In the drawings forming a part of this application we have shown a body casing 6, closed at its top where it is provided with the conventional screw-thread 7, and open at the opposite end, tapered as shown at 8, and said casing is also provided with a bore 9 adjacent its closed end opening into a larger bore 10 to form a shoulder 11, and longitudinally slotted in the position of said last named bore, as shown at 12, and the bore 10 opens into a circular recess 13 to form a shoulder 14, said recess being tapered inwardly and downwardly at its lowered end, as shown at 15, to approximately meet

the taper of the open end 8, the diameter of the casing at this point being approximately that of the bore 10, and said casing is also provided with a pocket 16 in the side thereof, in the position of the bore 9, and 60 in which rests a latch 17 normally forced toward the center of the casing by means of a spring 18.

Longitudinally movable in the bore 9 is a plunger-rod 19, closely fitting said bore, 65 having an enlarged head 20 recessed as shown at 21, and having an annular groove 22 beneath the latch 17 to form a shoulder 23 and a beveled surface 24, this being an important feature of the invention, and said 70 rod carries two collars 25 and 26 held in position by means of bolts 27 and 28, respectively, the former of which collar supports one end of a coil spring 29 which also abuts on the shoulder 11 and tends to force the 75 plunger downwardly in the casing; the collar 26, together with the shoulder formed by the head 20 of the plunger, serves to maintain a plurality of gripping jaws 30 in position, the lower ends of which are internally threaded, as shown at 31, and externally tapered as shown at 32 to conform to the taper 15 of the recess 13 whereby, in the downward movement of the plunger, the jaws 30 collectively act as a clutch for engagement with a tool which it is desired to recover, and the shoulder 14 prevents more than a predetermined degree of upward movement of the plunger in the casing. 85

The casing 6 is provided, above the upper 90 end of the plunger, with diametrically arranged bushings 33 having a transversely arranged pin 34 loosely held therein and projected over the end of the plunger, and imprisoned by means of screw-threaded 95 plugs 35, and said bushings are locked in position by means of small screws 36.

When a tool has become detached from the cable and rests within the well, usually at the bottom thereof, the device described, 100 hereinafter referred to as a socket, is connected with the cable and lowered into the well and, when the tool enters the casing 6 and the plunger head rests upon the upper end of said tool, said casing may descend 105 until the pin 34 rests upon the upper end of the plunger, thereby insuring the fullest expansion of the clutch formed by the jaws 30 and, when tension is placed upon the cable and the casing 8 drawn upwardly, the 110

taper 15 acting upon the taper 32 of the jaws 30 serves to force the said jaws into gripping engagement with the tool and which may, unless firmly held within the 5 well, be drawn upwardly thereby, out of the well. If, however, the tool resists this upward movement and cannot be dislodged, the cable is quickly slackened to permit the casing 6 to fall and, in such sudden fall, 10 the frangible pin 34 is broken off and the upper end of the plunger passes upwardly into the bore 9 beyond the normal position of the pin, this plunger movement carrying the annular groove 22 above the latch 17, 15 the beveled surface 24 permitting this, and, in the fall of the casing, the taper 15 passes below the taper 32 of the jaws 30, whereby they are no longer in gripping connection with the tool; when tension is again placed 20 upon the cable and the casing 6 drawn upwardly, the latch 17 is free to enter the annular groove 22 but, because of the shoulder 23, said plunger must rise with the casing, this latch engagement occurring before 25 the taper 15 has reached the taper 32 of the jaws 30, and the said jaws are thus released from the tool, and the socket, as a whole, may be withdrawn from the well, without the tool.

30 In Fig. 5 is shown a slight modification of the latch 17 which possesses the advantage of being enabled to be released from the tool without the use of the frangible pin required for the form shown and described 35 and is more particularly designed for sockets of relatively great diameter and consequent weight, a latch 37 being forced inwardly by means of a spring 38 and a removable plug 39 to engage the plunger 40 in the position of the annular groove 22; this latch has a small recess 40 in the end thereof and, in the retracted position of the latch shown, a trip 41 rests within said recess and bears upon the plunger-rod, said 45 trip being held in operative position by means of a spring 42 and a detachable screw-threaded plug 43, and it will be noted that the base of the trip is rounded, as shown at 44, whereby the latch trip may 50 swing on said base. The operation of this form is similar in all respects to that already described up to the point of unsuccessful tool withdrawal, the casing having descended to its downward limit, carrying 55 the trip 41 past and beneath the annular groove 22, and then drawn upwardly to cause the jaws to engage the tool, but, in this downward movement of the trip the spring thereof has forced the same into 60 the annular groove, but not releasing the latch 37, although said latch is permitted to be moved inwardly by its spring, the reason for this failure to release the latch being that the trip still remains in the 65 recess 40 and rests between the latch and the

reduced surface of the plunger-rod until, in its downward movement with the casing 6, it glides over the beveled surface 24 and forces the latch outwardly; however, when the casing 6 is drawn upwardly by the cable 70 to cause the jaws to engage the tool, the trip 41 strikes the shoulder 23 and is moved thereby out of the recess 40, the rounded base of the trip permitting this movement, and the latch then bears directly upon the 75 plunger-rod, but above the annular groove 22 and, if the tension be maintained on the cable, the tool is not released. If the tool resists withdrawal, the cable is slackened to permit the casing 6 to again descend, 80 thereby carrying the latch 37 below the annular groove and, when the cable is again subjected to strain, the casing 6 again moves upwardly until the latch strikes against the shoulder 23, this movement of the casing 85 being less than is required to actuate the clutch jaws, and the socket, as a whole, is free to be withdrawn from the well, but in the operation of attachment to a tool, the cable may be slackened but once with this 90 form unless it is desired to release the tool within the well. Both forms require one slackening of the cable to carry the parts into tool engaging position, one upward movement to withdraw the tool, and a second 95 slackening of the cable to release the socket from an immovable tool; both employ a latch in the casing, and a groove in the plunger, but the form last described is not adaptable to sockets of small diameters 100 as the casing walls are not sufficiently thick to accommodate the trip 41, although it possesses the advantage over the form first described of not destroying any portion thereof, as the frangible pin in the first 105 form.

The socket may be made of any size, and of any desired materials, and may also be constructed to accommodate the same to any tools not of the conventional form, but this is arbitrary as will be understood, the intent being to prevent the loss of the socket because of tools immovably held within a well, and we reserve the right to make any changes over the forms shown, within the 110 scope of the following claims, which do not depart from the spirit of the invention, nor sacrifice its advantages.

Having fully described our invention, what we claim as new, and desire to secure by Letters Patent, is:—

1. A device of the class described, comprising a casing, a plunger therein, a clutch carried by said plunger, means for actuating said clutch in the upward movement of said casing, means for preventing the operation of said clutch in the upward movement of said casing, and a frangible element for normally preventing the operation of said clutch prevention means. 115

2. A device of the class described, comprising a casing, a plunger therein provided with an annular groove, a clutch on said plunger, means on said casing for actuating said clutch, in the upward movement of said casing, a latch on said casing, and a frangible element preventing the entry of said latch into said groove, while unbroken, and means for breaking said frangible element.
- 5 3. A device of the class described, comprising a casing, a plunger therein provided with an annular groove, a spring for moving said plunger downwardly in said casing,
- 10 a plurality of flexible jaws on said plunger forming a tool clutch, the interior of said casing being tapered to actuate said clutch jaws inwardly, a latch on said casing, a frangible pin in said casing, above said plunger and normally maintaining said latch and groove at an inoperative distance from each other, and a detachable plug for permitting access to said pin to replace the same, and means for breaking said pin.
- 15 In testimony whereof we have signed our names to this specification.
- CHESTER A. RASMUSSEN.
ROBERT M. CLARK.
